UNITED STATES PATENT OFFICE.

GEORG ROLLWING, OF HANOVER, GERMANY, ASSIGNOR TO HEINRICH H. C. SCHNELLE,
OF WHEELING, WEST VIRGINIA.

FAUCET.

1,080,369.

Specification of Letters Patent.

Patented Dec. 2, 1913.

Application filed November 15, 1911, Serial No. 660,537. Renewed September 18, 1913. Serial No. 790,566.

To all whom it may concern:

Be it known that I, GEORG ROLLWING, a subject of the Emperor of Germany, and resident of Hanover, Germany, have invented certain new and useful Improvements in Faucets, of which the following is a specification.

This invention relates to improvements in faucets, and it has for its primary object to provide a faucet or cock having means whereby the flow of liquid therethrough may be cut off by turning the outwardly projecting valve stem in either direction.

A further object is to provide a faucet having two oppositely facing valves, either of which may be seated for preventing the passage of water.

A still further important object is to provide a faucet having means whereby a part may be disconnected for renewing the seat for the oppositely-facing valves, and having an auxiliary valve which seats automatically when said part is disconnected, thus avoiding the necessity for cutting off the water supply to the faucet prior to making such disconnection.

With these and other objects in view, the invention resides in the features of construction, arrangement of parts and combinations of elements which will hereinafter be fully described; reference being had to the accompanying drawings, forming a part of this specification, in which—

Figure 1 is a longitudinal section of the invention, showing one of the valves seated to prevent the flow of water; Fig. 2 is a similar section showing the valves unseated to admit the passage of water; Fig. 3 is a similar section showing another valve seated to cut off the flow; and Fig. 4 is a similar section showing the parts detached and the auxiliary valve seated.

Referring to said drawings, in which like designating characters distinguish like parts throughout the several views—1 indicates a faucet-body having an integral forwardly and downwardly curved spout 2. Threaded axially into said body from the front end thereof is a stem 3 which has upon its outer end suitable means by which it may be grasped for turning, as a hand-bar 4. A gland 5 is provided in the front end of the body 1 about the stem 3 whereby a packing 6 is maintained in position. The rear end of the body 1 is interiorly threaded and

has received therein the exteriorly threaded front end of a barrel 7 whose opposite end is adapted for connection with a water supply pipe or other source of liquid supply. Interposed between the outer end of the barrel and an annular internal shoulder 1^a formed in the rear end of the faucet body 1 is a ring or washer 8 of suitable material which constitutes a valve seat through which the admission of fluid to the faucet body is controlled by either of two oppositely-facing valves 9 and 10, the former located behind and the other in front of said seat. The rearwardly facing valve 10 may be carried by or formed integral with the stem 3, but is preferably separate therefrom, as shown, having an integral stem 11 whose end is loosely seated in a socket 12 provided in the inner end of said stem 3; thus, the wearing or grinding of the valve seat 8 incident to the turning of the valve into and out of seating position is avoided.

The valve 9 is mounted on the front end of a stem 13, and is normally held seated against the valve seat 8 by means of a spiral spring 14 interposed between said valve and an internal annular shoulder 15 formed adjacent to the rear end of the barrel. A forwardly projecting stem 16 is carried centrally on the front face of the valve 9 and has its front end loosely seated in a socket 17 provided in the face of the valve 10. Said stem 16 constitutes a distance-piece whereby said valves 9 and 10 are held separated, the length thereof being such that but one of said valves may be seated at one time.

Seated against an internal annular shoulder 18 formed in the rear end of the barrel 7 is a ring or washer 19, preferably of fiber, which constitutes a seat for an outwardly facing auxiliary valve 20 which is adjustably mounted on the rear end of valve stem 13. The valves 9 and 20 are so adjusted with relation to each other that both seat upon their respective seats 8 and 19 at one time, a double seal for preventing leakage of liquid to the interior of the faucet body being thus provided.

In practice, the stem may be turned forward or backward from the open position of the faucet depicted in Fig. 2 to close the faucet. When turned forward the valve 10 is thrust back against the seat 8, as shown in Fig. 1, and in such movement of the valve 10 the valves 9 and 20 are, through the

intermediacy of the stem 16, retired against the tension of the spring 14 to the position shown in said figure. When turned rearward, the valve 10 is further withdrawn 5 from its seat 8, allowing the valves 9 and 20, actuated by the spring 14 to move to seating position against valve seats 8 and 19, respectively, as shown in Fig. 3.

When it is desired to renew valve seat 8, 10 as when it becomes worn, this may be accomplished by simply disconnecting the faucet body 1 from the barrel 7, as shown in Fig. 4, and without disconnecting said barrel from its seat. As the valve 10 is withdrawn 15 from bearing engagement with the stem 13, the spring 14 draws the auxiliary valve 20 upon its seat 19 preventing access of water to the barrel 7. Thus, as is apparent, the renewal of the valve seat does 20 not require that the water supply be shut off prior to disconnecting the faucet.

From the foregoing it will be seen that I provide a faucet of exceedingly simple and practicable construction possessing various 25 novel features and manifest advantages.

Having thus described my invention, what I claim as new, and desire to secure by Letters Patent, is—

1. In a faucet, a barrel, a faucet body 30 detachably connected to said barrel, a valve seat at the entrance to said body, detachably-connected oppositely-facing valves operating to seat against opposite faces of said seat, said valves being independently adapted to 35 control the passage of fluid from said barrel to said faucet body, a stem upon the front end of which the rearmost of said valves is carried, a forwardly facing valve carried by the rear end of said stem, a valve seat at the 40 entrance to said barrel, the last named valve being adapted to engage the last named valve seat simultaneously with the seating of the valve on the opposite end of said stem, a spring controlling the movement of all of 45 said valves in one direction, and means for simultaneously moving all of said valves in the opposite direction.

2. A faucet comprising a body composed 50 of two detachably connected parts having communicating water passages, an apertured removable member interposed between said parts whose opposite faces constitute valve seats, a valve for seating against the rear face of said member, a spring normally 55 maintaining said valve seated, a valve for

seating against the front face of said member, means for moving the last named valve to its seat, a valve seat at the entrance to the rearmost part of said body, a valve for seating on the last named seat carried in fixed 60 relation to the first named valve, and a distance piece interposed between said valves whereby movement of said valves is rendered conjoint.

3. A faucet comprising a body composed 65 of two detachably connected parts having communicating water passages, an apertured removable member interposed between said parts whose opposite faces constitute valve seats, a valve for seating against the rear 70 face of said member, a spring normally maintaining said valve seated, a valve for seating against the front face of said member, means for moving the last named valve to its seat, a valve seat at the entrance to the rearmost 75 part of said body, a valve for seating on the last named seat carried in fixed relation to the first named valve and adapted to seat simultaneously therewith, and a distance piece interposed between the two valves first 80 named whereby movement of one of the latter is communicated to the other.

4. A faucet comprising a body composed 85 of two detachably connected parts having communicating water passages, an apertured removable member interposed between said parts whose opposite faces constitute valve seats, a valve for seating against the rear 90 face of said member, a spring normally maintaining said valve seated, a valve for seating against the front face of said member, means for moving the last named valve to its seat, a valve seat at the entrance to the rearmost part of said body, a valve for seating on the last named seat carried in 95 fixed relation to the first named valve, the last named valve being seated automatically by said spring when the parts of the faucet body are disconnected, and a distance piece interposed between the two valves first 100 named whereby movement of one of the latter effects a corresponding movement of the other.

In testimony whereof I affix my signature in presence of two subscribing witnesses.

GEORG ROLLWING.
